UNITED STATES PATENT OFFICE.

HENRY J. CHILTON, OF CHICAGO, ILLINOIS.

BOTTLE-WASHING APPARATUS.

1,260,329.

Specification of Letters Patent.

Patented Mar. 26, 1918.

Application filed August 22, 1912. Serial No. 716,363.

To all whom it may concern:

Be it known that I, HENRY J. CHILTON, a citizen of the United States, residing in the city of Chicago, county of Cook, and State of Illinois, have invented certain new and useful Improvements in Bottle-Washing Apparatus, of which the following is a specification.

The invention relates to improvements in bottle washing apparatus and refers more particularly to a machine of the so-called rotary type.

Among the salient objects of the invention are to provide a construction in which a series of bottles are automatically washed and then rinsed while moving with a traveling conveyer; to provide a construction in which the bottles after being washed and rinsed and while still in the conveyer are automatically inverted and delivered to a suitable transfer mechanism for filling; to provide a construction in which a plurality of bottles are carried by an endless traveling conveyer, first to the washing apparatus and there rotated synchronously with the latter and thence to a rinsing apparatus and there similarly rotated with the latter and then inverted and delivered to said transfer mechanism; to provide a construction in which the foregoing operations are all carried out during an uninterrupted travel of the conveyer, and in which the operations are all automatically performed; to provide a construction in which water is admitted to the brushes and rinsing apparatus at predetermined intervals by novel and improved types of automatically controlled valve mechanism; to provide a construction in which the various operating mechanisms are all or may be actuated from a single driven power; to provide a construction in which each brush and its coöperating parts forms a single unitary structure which can be inserted in place or removed from the machine without disassembling or rearranging any of the other parts; to provide a construction which can be readily adapted for use with bottles of various sizes, to provide a construction which is of a relatively compact form and nevertheless can handle a

maximum number of bottles in a given time; to provide a construction in which the operating mechanisms are in the main actuated by cams thus assuring a positive and reliable operation and in general to provide an improved construction of the character referred to.

The invention consists in the matters hereinafter described and more particularly pointed out in the appended claims.

In the drawings—

Figure 1 is a vertical sectional view of the washing, rinsing and transferring mechanism;

Fig. 2 is a horizontal sectional view taken on lines 2—2 of Fig. 1 and looking in the direction of the arrows;

Fig. 3 is a vertical sectional view taken at right angles to Fig. 1 and showing more particularly a portion of the filling apparatus;

Fig. 4 is a horizontal sectional view taken on lines 4—4 of Fig. 3 and looking in the direction of the arrows;

Fig. 5 is a sectional view taken just above the base of the washing and rinsing apparatus and filling apparatus;

Fig. 6 is a vertical sectional view on an enlarged scale of the washing apparatus;

Fig. 7 is a similar sectional view of the rinsing apparatus;

Fig. 8 is a horizontal sectional view taken on lines 8—8 of Fig. 7 and looking in the direction of the arrows;

Fig. 9 is a top plan view of the valve plate used in connection with the rinsing apparatus;

Fig. 10 is a fragmentary side elevation of one of the brush spindles and coöperating plunger mechanism;

Fig. 11 is a vertical sectional view taken on lines 11—11 of Fig. 10 and looking in the direction of the arrows;

Fig. 12 is a vertical sectional view taken on lines 12—12 of Fig. 10 and looking in the direction of the arrows;

Fig. 13 is a view similar to Fig. 10 but showing the brushes in elevated position and parts broken away to show the interior construction;

- Fig. 14 is a top plan view of the construction shown in Fig. 10;
- Fig. 15 is a horizontal sectional view taken on lines 15—15 of Fig. 10 and looking in the direction of the arrows;
- Fig. 16 is a horizontal sectional view taken on lines 16—16 of Fig. 10 and looking in the direction of the arrows;
- Fig. 17 is a horizontal sectional view taken on lines 17—17 of Fig. 10 and looking in the direction of the arrows;
- Fig. 18 is a horizontal sectional view taken on lines 18—18 of Fig. 10 and looking in the direction of the arrows;
- Fig. 19 is a fragmentary perspective view of one of the brush guides;
- Fig. 20 is a perspective view of a locknut used for securing one of the gear hubs of the brush spindles in place;
- Fig. 21 is a fragmentary view partly in section and partly in side elevation of the construction shown in Fig. 13 with the parts in the same position.
- Fig. 22 is a view partly in elevation and partly in vertical section showing one of the brushes and associated spindles, parts being broken away to reduce the size of the drawing;
- Fig. 23 is a perspective view of one of the brushes;
- Fig. 24 is a fragmentary perspective view of one of the brush spindles, and showing more particularly the socket into which the lower end of the brush fits;
- Fig. 25 is a perspective view of the lock block whereby each brush is keyed to the spindle;
- Fig. 26 is a horizontal sectional view taken on lines 26—26 of Fig. 6 and showing particularly the valve plate used in connection with the washing apparatus;
- Fig. 27 is a horizontal view taken on lines 27—27 of Fig. 6 and showing more particularly a portion of the valve mechanism co-operating with the valve plate shown in Fig. 26;
- Fig. 28 is a fragmentary perspective view of the adjustable plate used for confining the bottles in the holder, during the operation of washing;
- Fig. 29 is a side elevation of the safety break away mechanism associated with the washing apparatus;
- Fig. 30 is a horizontal sectional view taken on lines 30—30 of Fig. 29 and looking in the direction of the arrows;
- Fig. 31 is a perspective view of a drain trough used in connection with the washing and rinsing apparatus;
- Fig. 32 is a vertical sectional view of the idler mechanism used for tensioning the chain conveyer;
- Fig. 33 is a plan view looking down on lines 33—33 of Fig. 32;
- Fig. 34 is a side elevation looking from 65 the point shown on lines 34—34 of Fig. 32.
- Fig. 35 is a fragmentary horizontal sectional view showing the manner of constructing the conveyer chain and bottle holder;
- Fig. 36 is a view partly in side elevation and partly in vertical section of the construction shown in Fig. 35;
- Fig. 37 is a fragmentary side elevation of the conveyer chain and showing also a portion of the supporting tracks;
- Fig. 38 is a sectional view taken at right angles to Fig. 37 on lines 38—38 of said figure and looking in the direction of the arrows;
- Fig. 39 is a fragmentary perspective view of the transfer mechanism;
- Fig. 40 is a diagrammatic view showing the manner in which the bottles are inverted and then released from the conveyer;
- Fig. 41 is a diagrammatic view showing the manner in which the brushes are moved into and out of operative engagement with the bottles;
- Fig. 42 shows a modified form of one of 90 the bottle holders or cup forming part of the conveyer;
- Fig. 43 is a horizontal sectional detail of the rinsing mechanism;
- Fig. 44 is a top plan view partly in section of the main casting which connects the upper ends of the washing and rinsing apparatus;
- Fig. 45 is a view partly in side elevation and partly in section of part of the driving 100 mechanism;
- Fig. 46 is a fragmentary horizontal sectional view of one of the washing sets and the rotor main frame;
- Fig. 47 is a sectional detail view of a rotary valve disk and certain associated parts on line 47—47 Fig. 27.
- Referring to the drawings—
- 1 designates as a whole the main base casting, substantially rectangular in shape. 110 To this casting is rigidly secured a hollow standard 2 by means of a base flange 3. Upon the main base casting is also secured a pair of somewhat similar supporting standards 2' and 2''. At their upper ends 115 these three standards are connected by means of a top plate or casting 10, this plate having bosses 11, 12 and 13 which fit over the upper ends of the respective standards. The boss 13 is adjustably connected to the upper end of the standard 2' for a purpose hereinafter described. It may be here stated that the main standard 2 supports the washing mechanism, the standard 2'' the rinsing mechanism and the standard 2' supports an 120 idler sprocket.
- Describing now the mechanism supported by the standard 2, upon it is mounted a rev-

oluble rotary frame 4. In order to support the rotary main frame 4 the standard 2 is provided exteriorly with an annular shoulder 5 on which is mounted a thrust bushing 6 rigidly secured to the standard 2. The rotary main frame is provided with an annular collar 7 having at its lower end an outwarded flange 8 which fits over the bushing 6. Between the flange 8 and the bushing 6 is interposed a washer 9. The upper end of the rotary frame 4 is provided with an annular sleeve 14 which fits around the main standard 2. This sleeve 14 is provided with an annular shoulder 15 on which is rigidly supported a sprocket gear 16. This sprocket gear 16 takes the form an annular hollow casting, the lower end of which is provided with a series of forked sprocket teeth 17 and 18 as shown more clearly in Fig. 6. On the upper end of this sprocket is adjustably mounted a stop plate 19 provided with a screw threaded flange 20 which engages a similar threaded portion 21 on the sprocket. This plate 19 serves to limit the upward movement of the bottles as they pass around the sprocket, as will hereinafter more clearly appear.

On the outer end of the rotary main frame 4 is supported a series of bottle washing sets designated as a whole 22. Each of these sets is complete in itself and detachably connected to the main frame so that each set may be removed or inserted in place independently of the other sets. Each set comprises a pair of tubular posts 23 and 24 rigidly connected at their upper ends by a casting 25 and at their lower ends by a base member 26. Within each of these posts 23 and 24 is mounted a reciprocating tubular sleeve 27. Within the upper end of each of these sleeves 27 is a plug 28 for centering the sleeves 27 on the pullrods 29. Just above the head 25 each of the sleeves 27 is provided with a somewhat similar stop plug 30. On each rod 29 is a coiled compression spring 31, the lower end of which abuts against another plug 32 which is rigidly supported in the main tubes 23 and 24 respectively. The lower ends of these rods are connected by a cross link 32' which works in suitable slots 31' in the side of the tubes 23 and 24. To the upper ends of the rods by means of nuts 33 is secured a bottle supporting member 34 which also serves as a catch basin. This supporting member 34 is provided with an apertured boss 35 in which is mounted a revoluble tubular member 36. The upper end of this tubular member 36 is provided with an enlarged head portion 37 for receiving the corresponding bottle centering members 38. Each of these bottle centering members comprises a bell-shaped mouth portion 39 and down turned flange portion 40. The centering device is pro-

vided with ears or lips 41 which are secured 65 to the catch-basin by means of screws 42 as shown more clearly in Figs. 12 and 14. It will be noted that the head 37 of the tubular member 36 is also provided with a down-turned flange 37'. The arrangement is such 70 that when the water is drained from the bottles it will be drained into the catch basin and will not splash out into the room.

The lower end of each tubular member 36 fits into a sleeve 43 and is keyed thereto by 75 means of feathers 44 fitting in grooves 45 formed in the interior of the sleeve 43. The lower end of each sleeve 43 is provided with a spur gear 46 driven by main driving gear hereinafter described. In order to prevent 80 any water from leaking through the sleeve into the bearing parts, to the upper end of the sleeve 43 is screw threaded a cap 47. The lower end of each tubular guide member 36 is provided with a squared bore 48 to receive 85 the brush spindle 49, which is similarly squared in cross section. The brush spindle is thus locked against rotation independently of the guide 36, but can reciprocate vertically independently of the guide. In 90 order to form a water tight fit between the guide 36 and the brush spindle 49, the lower end of the guide member is provided with a screw threaded reduced extension 50 on the lower end of which is screwed a cap 51. Between the cap and extension 50 is interposed a packing 52. From the foregoing it will be seen that the tubular guide member 36 rotates with the gear sleeve 43 but has reciprocatory vertical movement independently of 100 the sleeve, and that the brush spindle 49 also rotates with the guide member 36 and gear sleeve, but has vertical movement independently thereof.

The lower end of each hollow brush spindle 49 is connected to a traveling cross head 53 by means of a hollow tubular extension 54, the upper end of which extends into the lower end of the spindle as shown at 55, and the lower end of which is connected to the cross head 53 by means of a stuffing box 56. The cross head 53 is cored as shown at 57, the upper end communicating with the hollow extension 54 and the outer end of the cored portion connected to a flexible hose 115 58 in a manner hereinafter described.

The cross heads 53 are raised and lowered during the travel of the machine in the following manner:—On the tubular guide posts 23 and 24 is loosely mounted a supplementary reciprocating cross head 59, preferably having a bearing sleeve 60, rigidly secured to the cross head, the lower end 60' of the sleeve fitting loosely into the main cross head 53. To one side of the supplementary cross head 59 is screw threaded as shown at 61' a journal stud 62 having at its outer end a hexagonal confining flange 65.

On the journal studs 62 is rotatably mounted a cam roller 63. To the cam roller 63 is rigidly secured a bushing or bearing ring 64 which fits over the stud 62. The supplementary cross head 59 is connected to the main cross head 53 in the following manner: To the main cross head 53 is screw threaded as shown at 66 a block 67. To the opposite sides of this block is riveted at 68 a pair of spring clips 69. The upper ends of these spring clips are adapted to receive and hold locking lugs 70 which are secured by screws 71 to the supplementary cross head 59. The arrangement just described is such that normally the cross heads move as a unit and accordingly when the cam roller 63 rides up the cam track, in a manner hereinafter described, the cross heads will be carried upwardly and the brush spindle raised until the brush enters the bottle. If for any reason however, the brush spindle or brush should meet an obstruction while the same is being raised, the locking lugs 70 will pull out of the springs 69, whereupon the supplementary cross head 59 will move upwardly without moving the main cross head and connected parts.

As the cross heads move upwardly, the cross connecting link also moves upwardly by reason of the compression spring 31. These compression springs then automatically carry the guide members 27 upwardly and with them the centering member 38, until the bottle engages the top plate 19. This arrests further movement of the centering member, the brush spindle however, continues to move upwardly until the brush enters the bottle, the spindle being carried upwardly during further raising of the cross heads. As the cross heads move downwardly they withdraw the brush from the bottles and the parts are so arranged that just as the brushes leave the bottles and regardless of the length of the latter the cross heads engage the cross links 32' and carry the centering member 38 down with the brush. As long as the cross heads remain in their lowered position, the brush and centering members are likewise held in their lowered position.

Describing now the manner in which the brushes are connected to the spindle, within the upper end of the latter is rigidly secured a squared block, 72, provided with a central bore 73 to permit water to pass out of the upper end of the spindle. The block is provided with a reduced extension 74 to which is secured an annular spring socket member 75 having a flaring mouth 76. This socket member 75 is adapted to receive a central plug 77 to which the brush 78 is secured. The plug 77 is provided with an annular groove 79 which has spring locking engagement with the upper end of the spring socket member 75. The plugs are

locked against turning in the socket by means of the lugs 80 which fit into suitable grooves 81 formed in the extension 74. By this safety break-away mechanism, that if for any reason the brushes should become lodged in the bottles as they are being withdrawn therefrom they will snap loose from the spindles as the latter are positively pulled down by the cross heads.

Each of these washing sets just described is independently secured to the rotary main frame by means of screw bolts 82 extending through the main head 25 and into the outer side of the rotary main frame. The base member 26 of each washing set is secured rigidly by a screw bolt 26' to a centering ring 83 which revolves around the flange 84 of the main base 1. As heretofore described, the brushes are raised and lowered by means of the cam rollers 63 riding on a cam track. This cam track designated as a whole is mounted as shown at 86 on the base casting 1, and comprises a horizontal portion *a*, inclined raised portion *b*, removable intermediate section *c*, inclined portion *d* and end portion *e*. As the cam rollers ride around this track the brushes are alternately carried into and out of the bottles as will hereinafter more clearly appear when describing the operation of the machine.

Referring now to the manner in which water is fed to the brushes, a bracket arm 87 is supported on the base casting 1, and is provided at its upper end with an extension 88 which fits around the main standard 2 and forms an annular valve seat. This valve seat 88 is provided with a segmental groove 89 which communicates with a main supply channel 90 (dotted line Fig. 26). The lower end of this channel 90 communicates with a similar supply conduit 91 formed in the main base casting 1. The discharge of water through the valve groove 89 is controlled by a rotary valve plate 92 rotatably mounted on a bushing 93 which is rigid with the bracket member 87. The rotary valve disk 92 is provided with a plurality of discharge passages 94, the outer ends of which are connected to flexible pipes 58 heretofore described. While each of these apertures 94 is passing by the segmental groove 89 the water will be forced into this pipe 58. In other words, each brush will receive water during the time that the corresponding port in the valve member 92 is passing by the segmental groove 89. To prevent water from spouting out from the valve member in case of leakage, the rotary valve plate 92 is provided at its outer edge with a down turned lip 94'. In order to have a water tight fit between the valve disks, the rotary valve member 92 is held in spring pressed engagement with the other member by means of a coiled expansion spring 95, the lower end of which abuts

against the member 92 and the upper end of which is confined by means of a collar 96 screw threaded on the upper end of the bushing 93.

- 5 Describing now the manner in which the rotary main frame is driven, on a main driving shaft 97 is mounted a fast and loose pulley 98 and 99 for receiving a driving belt from any source of supply (not shown).
- 10 The pulley 98 is provided with an extension 100 carrying a spur gear 101 which meshes with a similar gear 102 mounted on a parallel counter shaft 103. The inner end of the shaft 103 carries a bevel gear 104 which 15 drives a bevel gear 105 rigid with the sleeve 106, surrounding the main standard 2. On the upper end of the sleeve 106 is fixedly mounted a common driving gear 107 which actuates the gears 46 of the brush sets. The 20 bevel gear 104 also meshes with a bevel gear 108 secured to the lower end of the main vertical driving shaft 109 which extends through the main standard 2. This main vertical driving shaft 109 is journaled in 25 bearings 110 and 111 secured in the lower and upper ends of the standard 2. On the upper end of the vertical shaft 109 is keyed a pinion 112 which meshes with an idler pinion 113. This idler pinion 113 is rotatably mounted on a journal pin 114 which is secured to a plate 115 mounted by bolts 116 to the top plate 10. The idler pinion 113 is rigid with a pinion 117. The last named pinion in turn meshes with a pinion 118 30 mounted on a bushing 119 seated in and rigid with the top plate 10. The plate 115 is slotted as shown in order to permit of bodily movement relative to the plate 10 in the case gearing of different size is used.
- 35 The pinion 118 is provided at its upper end with an annular extension 120 having oppositely disposed locking recesses 121. The locking recesses 121 are adapted to receive spring clips 122 (Fig. 30) carried by a cap member 123 and secured thereto by screw bolts as shown at 124. In this top cap member 123 is rigidly secured an extension 125 of a vertical drive shaft 126. This shaft extends through the sleeve or bushing 119 and 40 is provided at its lower end with a spur gear 127. The spur gear 127 meshes with a gear 128 carried by the upper end of the sleeve 14. It will be remembered that this sleeve 14 forms an extension of the main rotary frame 4 and is also rigidly connected to the sprocket gear 16. Accordingly, the rotation of the spur gear 128 rotates both the revolute frame 4 and sprocket 16. The action of the spring clips 122 is such that normally 45 they lock and grip the shaft 125 and the gear 118 and extension 120. If, however, during the rotation of the washing mechanism an obstruction is met the clips will snap out of the recess 121 and the shaft 125 50 will not rotate. This safety break-away
- mechanism may be somewhat varied in its details of construction but forms an important feature of the invention.
- Describing now the rinsing mechanism, upon the standard 2" is mounted a sleeve 129 provided near its lower end with a rotary valve disk 130. This valve disk is radially cored as shown at 131, and is provided at its periphery with a series of nozzles 132 which communicate with the upper ends of the cored portion 131. Above the nozzles are secured as shown at 133 bottle centering members 134 which are adapted to catch and center the necks of the bottles as they pass around the rinser. The standard 2" is provided intermediate its height with an annular flange 135 on which is rigidly secured a stationary valve disk 136. This valve disk is provided at its upper face with a segmental groove 137 which registers with the lower ends of the cored portions 131 as the rotary valve disk revolves. The groove or recess 137 is connected to a main water supply pipe 138 by an inlet passage 139 formed in the stationary valve disk 136. The lower end of the main pipe 138 leads to the hollow portion 140 of the standard 2", which is in turn connected to a supply pipe 141 in the main casting. In order to spray the necks of the bottles a hollow segmental-shaped casting 142 is mounted adjacent the lower end of the bottles and perforated at its inner face as shown at 143. The lower end of this casting 142 is connected to the main supply pipe 138 by means of a branch pipe 138'. To rinse the upper ends of the bottles a second branch pipe 144 leads from the casting 142 to a hollow segmental casting 145 which extends over the upper ends of the bottles and is perforated at its inner edge as shown more clearly in Fig. 7. These hollow castings or rinsers 142 and 145 may be connected to a guard plate 146 which is secured at its lower end to a drain trough 147. This drain trough is supported on an annular flange 148 rigid with the main standard 2". The sleeve 129 is provided at its upper end with a bevel gear 149 meshing with a bevel gear 150 secured to the outer end of a counter shaft 151. The shaft 151 is journaled in the top plate 10 and is provided with a bevel gear 152 at its inner end which meshes with another bevel gear 156. The gear 156 is driven through the gears 127 and 128 heretofore described. The arrangement is such that the rotary valve member of the rinser is rotated in timed relation with the rotation of the washing apparatus. Rigid with the sleeve 129 and rotating therewith is a sprocket member 157, the sprocket teeth 158 of which are forked as shown more clearly in Fig. 2. The conveyer chain hereinafter described extends around the sprockets 157 and 16 and also around similar sprockets 130

159 mounted on the standard 2'. This sprocket 159 is laterally adjustable relative to said standard in order to regulate the tension of the conveyer chain. To this end the upper end of the standard 2' is provided with a casting 160 having a slideway 161 in which is adjustably mounted the base 162 of a supporting post 163. The base 162 is rigidly fixed to the slideway in any position of adjustment by means of an adjustable screw 164. The upper end of the post 163 is provided with a reduced extension 165 which is secured by means of nuts 166 and washer 167 to a slotted guide way 168 in the top plate 10. On a shoulder 169 of the post 163 is loosely mounted the idler sprocket wheel 159.

The conveyer chain after it travels around the sprocket wheel just described leads to a fourth sprocket wheel 170 rigid with a sleeve 171. This sleeve 171 is rotatably journaled on an extension 172 of a main supporting post 173 which is connected at its lower end to the main base casting 1.

25 Describing now the conveyer chain, which forms the support for the bottles and which is trained around the sprockets heretofore described, it comprises a series of cup-shaped links 174, provided at either side with an annular journal extension 175 rotatably mounted on trunnions 176. These trunnions are provided at their inner edges with a flange 177 which abuts against a shoulder 178 of the cup and are thus confined in position. One trunnion of each cup is provided with a forked extension 179 which fits over a single extension 180 of the adjacent trunnion and is pivotally connected to the extension by means of a pin 181. The arrangement is such that the cups are linked together not only to form a flexible chain or conveyer but have also rotary movement whereby they can be turned over in order to discharge the bottles from the conveyer in a manner hereinafter described.

45 Describing now the track on which the endless traveling conveyer is supported, a plurality of standards 182 are suitably fastened to the base casting 1. At the upper end of each of these standards 182 is bolted as shown at 183 a forked bracket arm 184. To the upper end of this forked bracket arm is riveted as shown at 185 a pair of angle irons 186, the horizontal flanges of which forms a direct track for the rollers 187 of the conveyer. As shown more clearly in Fig. 35 these rollers are pivotally mounted at opposite sides of the conveyer cups, in order to keep the pins 175 in a vertical position during the main travel of the conveyer. Each of these is provided at its lower end with a roller 188 which is confined between a pair of guide plates 189 suitably fastened to the forked bracket arms 184.

60 65 From the foregoing it will be seen that

while the conveyer is traveling along the main track the bottle holders or cups are in the position shown in Fig. 36, namely, with their necks extending downwardly. Preferably the bottle holders are provided with a rubber or other flexible lining 190.

To collect the water from the washing and rinsing apparatus, to the stationary main frame is secured a drain trough designated as a whole 191. This trough comprises two annular portions 192 and 193, one of which extends around the washing apparatus and the other one around the rinsing apparatus. The member 192 is provided with a removable section 194 in order that access may be had to the washing sets to remove them if desired. Above the drain trough each washing set is provided with a pair of superimposed drain plates 195 and 196 which catch any water on that part of the machine and drain it into the trough. This prevents water from reaching the working parts of the machine.

The conveyer chain first passes around the idler sprocket 159, thence around the sprocket 90 of the washing apparatus, thence around the sprocket of the rinsing mechanism and back to and around the sprocket 170 of the transfer apparatus. The manner in which this chain is trained around the various sprockets 95 is shown more clearly in Fig. 2. As the conveyer cups ride out of the track members 186, the outer rollers engage an inclined track member 197 which partly rotates the cup a quarter of a turn on the trunnions 100 176. As the outer rollers ride off the inclined section 197, the inner rollers engage a second inclined track segment 198 which turns the cup another quarter of a turn, whereupon the bottle is inverted to upright 105 position. The rollers then ride on a flat track segment 199 and during this travel the bottles slide down an inclined stationary cam 200 into the bottle holders 201. These bottle holders 201 are secured to a rotary, 110 supporting plate 202 which is connected to the main standard 173 by connecting ring 203.

Referring again to the main conveyer after the bottles have been released from 115 the cups, the rollers of the conveyer cups engage another track segment 204 and are reversed a quarter of a turn. The opposite rollers then engage another track segment 205 whereupon the bottles are returned to 120 normal upright position. The conveyer chain then rides on to the opposite side of the track and around the idler sprocket 159 as theretofore.

It will be remembered that after the bottles 125 left the main conveyer they were delivered to the holders 201 of the transfer mechanism. During the rotation of the transfer mechanism the bottles are held in their holders by means of a curved sta- 130

tionary guide plate 206 which is supported from the cam track of the transfer mechanism. The bottles are delivered from the transfer mechanism to a filling mechanism 5 207 shown in Fig. 4 and in fragment in Fig. 3. As the details of this mechanism form no part of the present invention they need not be discussed here in detail. This filling mechanism however is provided with a plurality of bottle holders 208 and is actuated in timed relation with the transfer mechanism by means of a pair of shafts 209 provided with intermeshing bevel gears 210, 211, and 212, the last mentioned gear meshing 10 with the gear 108 of the washing apparatus. The outer end of one shaft 209 is provided with a worm gear 213 which meshes with gear 214 connected to the main vertical shaft of the filling mechanism. The bottles 15 are automatically delivered from the transfer mechanism to the filling mechanism in the following manner: To the standard 173 is secured a plurality of radially disposed bracket arms 215 to the outer end of which 20 is secured a curved cam track 216, the construction of which is shown more clearly in dotted lines in Fig. 4. In the plate 202, which is preferably made up of a plurality of sections 202' is mounted a series of ejectors 217, which are normally forced outwardly by means of coiled expansion springs 218, there being one of these ejectors for each bottle holder 201. The ejectors are held retracted by means of cam rollers 219 suspended from the ejectors by through bolts 220 as shown more clearly in Fig. 3. As the bottle holders 201 approach the filling mechanism during their rotation, the cam track is so arranged that the ejectors are 30 gradually released and forced outwardly by springs, arranged so that the bottles are delivered to the filling mechanism positively in such a way as to avoid any danger of breaking. As will be seen in the drawings 35 means are provided for lubricating the various operating parts of the machine. To lubricate the main driving bearings of the washing apparatus proper, the main standard 2 is vertically cored as shown at 221, the lubricant being delivered to the passage 221 by grease cup 222. The lubricant passes 40 from the core 221 to the operating parts by means of cross ducts 223. To lubricate the bottle washing sets proper, the main rotary frame is provided with an annular groove 45 224 to receive the lubricant. From this groove a plurality of ducts lead to the washing sets, there being three of each of these ducts, designated, 225, 226, 227 for each set. 50 The grease cups 228 deliver lubricant to the main groove 224.

To lubricate the cross heads 53 and 59, to the outer end of each pin 61 is connected a grease cup 229 which delivers lubricant to 55 the roller 62 by ducts 230 and 231, as shown

in Fig. 17, and also to the cross heads by ducts 232 and 233. The grease cup is preferably of the compression type.

In Fig. 42 I have shown the manner in which the cups may be adjusted for varying 70 sizes of bottles, this is done by inserting a rubber or other flexible bushing 234.

Describing now the operation of the apparatus, the bottles are inserted in the conveyer at the beginning 8, travel around the idler sprocket 159 and thence around the washing apparatus. During their travel 75 around the washing apparatus, the brushes are raised into the bottles, and the interior of the bottles washed. It will be understood 80 of course, that the bottles are being washed during the travel of the rotary main frame of the washing apparatus. Just before the bottle holders leave the sprocket of the washing apparatus the brushes are withdrawn by 85 the action of the cam heretofore described. The conveyer then travels around the rinsing apparatus and the bottles are rinsed exteriorly and interiorly during their travel 90 around the rinser. The bottles then travel down to the transfer apparatus. During their rotation around the transfer apparatus they are inverted and removed from the cups into the holders of the transfer mechanism. During further movement of the bottles on the 95 transfer mechanism, they are ejected into the holders of the filling mechanism and after being filled are shunted out as shown in Fig. 4 by means of the trough-like guide-way 208.

The invention is not limited to the details of construction shown, as in its broader aspects the details of construction may be widely varied.

I claim as my invention:

1. In a bottle handling apparatus, the combination with a rotary main frame, of an endless chain conveyer extending around said frame and leading to points remote therefrom, a support for said chain conveyer 110 at said remote points, a plurality of washing sets connected to said main frame, each of said sets comprising a pair of reciprocatory guide members, a bottle centering member carried by said guide members, a hollow brush spindle, a brush in the upper end of said spindle, means for reciprocating said spindles and guide members to raise and lower the brushes and centering devices, and mechanism for operating said parts in timed relation.

2. In a bottle handling apparatus, the combination with a rotary main frame, of a plurality of bottle washing sets carried by said main frame and extending around the 125 same, each set comprising a pair of reciprocatory guide members, a centering member, a brush member, an endless chain conveyer extending around said rotary main frame and leading to points remote from 130

said rotary main frame and bottle holders carried by said endless traveling conveyer.

3. In a bottle handling apparatus, the combination with a rotary main frame, of an endless chain conveyer extending around said main frame, and leading to points remote therefrom, bottle holders carried by said conveyer, washing mechanism extending around said rotary main frame and hav-

ing a plurality of brush spindles and means 10 for raising the spindles out of the bottles and centering them and break-away mechanism associated with the brush spindles.

HENRY J. CHILTON.
